UNITED STATES PATENT OFFICE.

PHILIP W. PULIG, OF PHILADELPHIA, PENNSYLVANIA.

BAG HOLDER.

1,427,122.

Specification of Letters Patent. Patented Aug. 29, 1922.

Application filed October 20, 1921. Serial No. 502,916.

To all whom it may concern:

Be it known that I, PHILIP W. PULIG, a citizen of the United States, residing at Philadelphia, county of Philadelphia and 5 State of Pennsylvania, have invented certain new and useful Improvements in Bag Holders, of which the following is a specification, reference being had to the accompanying drawings.

10 My invention relates to holders useful in hanging up clothes bags and the like.

The main object of my invention is to provide a simple and efficient means capable of being readily and quickly attached about 15 the mouth of a bag, and, when hung up, of supporting the bag in suspension with the mouth of the same held open for convenience of access in filling.

Other objects and attendant advantages 20 will become readily apparent from the detailed description of a typical embodiment of my invention which follows:

In the drawings, Fig. I is a perspective view showing the manner in which a clothes 25 bag is supported by a holder conveniently embodying my invention; and

Fig. II is a perspective view on an enlarged scale of the holder alone.

The holder herein shown as typical of my 30 invention is in the form of a loop 1 which in practice is preferably constructed of a single piece either of stout wire or bar metal depending upon the size of the bag and the weight which is to be supported.

35 In the course of formation of the holder, a perpendicularly turned arched bend is made as at 2 for service as an eye whereby the holder may be hung to a fixed headed projection or peg such as indicated by the 40 numeral 3 in Fig. I of the drawings.

The sides of the offset or eye 2 converge toward the bend in the eye for cooperation with the peg in a manner to be presently noted.

45 It is to be especially noted that the bending is so ordered that an interval 4 is left between the ends 5, 5 of the wire or metal of the loop preferably at a point directly opposite the eye 2, and that said ends are 50 inclined slightly downward as clearly shown in Fig. II. These provisions are made with a view toward facilitating attachment of a bag of the type represented at 6 in Fig. I.

As shown, said bag has about its top, a 55 tubular band 7 within which the loop of the holder is accommodated. The band 7 is

interrupted as at 8 to afford an opening for the protrusion of the eye 2. In attaching the bag, one end 5 of the loop is introduced into the band 7 of the bag through 60 the opening 8 (the downward declivity of the end facilitating this operation) whereupon said band is worked or progressed until fully engaged by the holder.

In order to avoid undue projection of 65 the holder beyond the wall or surface to which it is hung, the loop 1 is made approximately oval or elongated preferably with straight parallel sides and rounded ends as shown in the illustrations, perfect 70 symmetry and balance being maintained by preordering the location of the interspace 4 and the eye 2 at the centers of the straight sides. When a holder of this form is hung up, its continuous straight side rests against 75 the wall and in cooperation with the perpendicularly turned eye 2 tends to stabilize the structure by preventing swinging about the projection or peg 3 as a pivot.

As the bag is filled the weight carried 80 tends to bend the curved ends of the loop downwardly, but this tendency to flexure of the loop is offset by the opposing influence of the converging sides of the eye 2 with respect to the peg upon which it is 85 supported, so that the curved ends of the loop are urged toward separation. In this manner the sag at the ends of the loop is prevented and the loop is maintained substantially in a horizontal plane independently 90 of the weight carried.

From the foregoing it will be apparent that a holder constructed according to my invention is extremely strong and durable and capable of being expeditiously and 95 cheaply manufactured.

Having thus described my invention, I claim:

1. A bag holder comprising a single strand of wire bent to form an elongated loop 100 with opposed substantially straight sides and rounded ends, the terminals of the strand terminating in closely spaced relation centrally of one of the straight sides, and an off-set at the other straight side of the 105 holder directly opposite the terminals formed by bending the wire to produce an open sided eyelet, whereby the holder may be enclosed within the interrupted hem around the mouth of a bag by inserting 110 one end in the interrupted portion and working the hem completely around the holder

and around the eyelet, the latter being adapted to protrude through the interrupted portion of the hem for suspension upon a peg.

- 5 2. A bag holder, comprising an elongated loop having straight sides and curved ends constructed of a single strand of wire or the like, and having a space toward the ends of the wire along one of the straight 10 sides of the loop so that the ends thereof may be inserted in the hem of a bag, and a perpendicular offset formed in one of the straight sides of the loop at a point opposite the space, said offset having converging 15 sides whereby the bag holder may be sup-

ported upon a peg by inserting the latter within the offset, the ends of the loop being supported against sagging by the tendency of the converging sides of the offset acting to urge the ends of the loop apart against 20 the opposing tendency of the weight carried by the bag to move said ends of the loop together.

In testimony whereof I have hereunto signed my name at Philadelphia, Pennsyl- 25

vania, this 18th day of October, 1921.

PHILIP W. PULIG.
